UNITED STATES PATENT OFFICE

WILLIAM E. BIHL AND AXEL RAMCLAW, OF CHICAGO, ILLINOIS, ASSIGNEES, BY MESNE ASSIGNMENTS, TO ZEROZONE, INCORPORATED, OF CHICAGO, ILLINOIS, A CORPORATION OF DELAWARE

COMPRESSOR MOUNTING

Application filed March 3, 1930. Serial No. 432,917.

This invention relates to mechanical refrigerators, and has to do more particularly with the mounting of the compressor unit.

In mechanical refrigerators of known type, which employ an electric motor for driving the compressor, a certain amount of vibration is unavoidable. This vibration is apt to be transmitted to the frame and casing of the refrigerator structure, resulting in undesirable noise. In mechanical refrigerators it is highly desirable that the vibration incident to the operation of the compressor unit be damped out as far as possible both to assure quiet operation and eliminate objectionable vibration.

Metallic contact between the compressor mounting and any part of the refrigerator frame or casing is particularly objectionable as causing a metallic rattle in the operation of the compressor unit. One of the main objects of our invention is to provide simple and efficient means for supporting the compressor unit in such manner as to effectively damp out the vibrations incident to the operation of such unit. A further object is to provide means whereby metallic contact between the supporting means for the compressor unit and the elements of the frame or casing of the refrigerator is prevented. A further object is to provide supporting means of the character stated of simple and inexpensive construction and which is adapted to permit ready removal and replacement of the condenser and associated parts as a unit. Further objects and advantages of the invention will appear from the detailed description.

In the drawing:

Figure 1 is a horizontal sectional view through the lower portion of a mechanical refrigerator of known construction, the compressor unit and associated parts being shown in plan; and

Figure 2 is a sectional view, on an enlarged scale, taken substantially on line 2-2 of Figure 1.

We have illustrated our invention as applied to a mechanical refrigerator comprising a sheet metal casing 1 suitably secured, ad-

jacent its lower end, to an angle iron frame 2 of rectangular shape in plan.

A pair of angle rails 3 are riveted or otherwise suitably secured to frame 2 and extend across the same from front to back of the casing. These rails are suitably spaced for reception of a rectangular base plate 4 upon which is mounted the compressor unit. This unit comprises a compressor 5, condensing coil 6, an electric motor 7, a thermostatic switch 8, and associated parts. The compressor unit is, in general, of known construction and is disclosed more fully in our copending application for compressor mounting, Serial No. 231,875, filed November 8, 1927. The compressor unit may be of any suitable or preferred type and need not be further illustrated or described here, it being sufficient to note that a suitable type of compressor unit is mounted upon the base plate 4.

The base 4 is preferably in the form of a casting and comprises a top plate 9 of rectangular shape having a depending peripheral flange 10 and provided at each corner with a depending boss 11. The bosses 11 are each suitably cored out from its lower end to provide a socket comprising a lower cylindrical portion 12 and an upper upwardly tapering portion 13. The lower portion 12 of each boss receives a thick rubber collar 14 disposed about a bolt 15 which passes through lower flange 3a of rail 3, a nut 16 being screwed onto the lower end of this bolt.

A fibre washer 17 is confined between head 18 of the bolt and the upper end of collar 14, it being noted that the washer 17 is of an appreciably greater diameter than the head 18 of the bolt. An upwardly tapering cushion member, in the form of a plug 19 formed of rubber or other suitable cushioning material, fits into the upper portion 13 of the socket and has its under face concave as at 20. An expansion coil spring 21 seats upon the upper end of collar 14, the lower end of this spring extending about the fibre washer 17 in contact with the circumferential surface thereof. The upper end of this spring seats in the concave under surface of the rubber plug 19.

It will be noted that the rubber collar 14

is spaced a slight distance away from the surrounding walls of lower portion 12 of the socket in boss 11, this space being slightly less than space 22 between vertical flange 3b of rail 3 and the adjacent end flange of base 4. The spring 21, in addition to being spaced well away from head 18 of the bolt, is also spaced well away from the surrounding wall of boss 11. By this construction metallic contact between the base 4 and rail 3 is prevented, and metallic contact between spring 21 and the boss 11 of the head of the bolt is also prevented. The springs 21 are well adapted for supporting base 4 and the compressor unit mounted thereon in such manner as to permit of sufficient yielding thereof to effectively damp out vibrations due to operation of the compressor.

This damping action of the springs is supplemented by the cushioning effect of the rubber collar 14 and the rubber plug 19. We find that it is not practicable to support the base 4 by rubber cushioning members alone, since rubber, under compression, has comparatively slight resiliency. Also, rubber is not well adapted, mechanically, for supporting a structure of this character. By our construction we obtain the benefit of the cushioning effect of the rubber as well as the benefit of the relatively great resiliency of the supporting spring 21.

The means for supporting the base 4 is of comparatively simple construction, and any of the elements of this supporting means can be readily removed and replaced as required. It is also to be noted that the base 4 is free from the spring 21 so that the compressor unit, including the base 4, can be readily removed from the casing 1 and replaced there-in. For this purpose the casing is provided with a removable panel 23 which is removably secured in the casing in a known manner. By raising the base 4 slightly the entire compressor unit can be removed through the opening provided by the removal of panel 23 and can be replaced through such opening.

What we claim is:

1. In combination, a supporting member, a base disposed above the supporting member and provided with a downwardly opening socket, a cushion member secured to the supporting member and projecting into said socket to limit the lateral motion of the base on the supporting member, a cushion member disposed within the socket, and a cushion spring confined between the two cushion members for supporting the base upon the support, said spring being spaced away from the surrounding wall of the socket.
2. In combination, a supporting member, a base member above the supporting member and having a downwardly opening socket, a cushion member seated upon the supporting member and extending into the lower end of said socket, a bolt extending through

the cushion member and securing it to the supporting member, a nonmetallic washer confined between the head of the bolt and the upper end of the cushion member, a second cushion member disposed within socket, and a cushion spring confined between the two cushion members and spaced away from the surrounding wall of the socket, the washer being of greater diameter than the head of the bolt and the lower end of the spring seating about the washer, said spring being spaced away from the head of said bolt.

3. In combination, an angle supporting rail comprising a vertical flange and a horizontal flange, a base disposed above the horizontal flange and having a downwardly opening socket, a cushion member secured upon the upper face of the horizontal flange and extending into the lower end of the socket, a cushion member disposed in the upper end of the socket, and a cushion spring confined between said cushion members and spaced from the surrounding wall of the socket, the lower cushion member being disposed to contact the surrounding wall of the socket and thereby limit movement of the base in the direction of the vertical flange of the rail.

4. In combination, an angle supporting rail comprising a vertical flange and a horizontal flange, a base member disposed above the horizontal flange and having a downwardly opening socket, a cushion member secured upon the upper face of the horizontal flange and extending into the lower end of the socket, a second cushion member in the upper end of the socket, the under face of said second member being concave, and a cushion spring confined between the two cushion members and spaced away from the surrounding wall of the socket.

5. In combination, a frame, angle rails secured to the frame in spaced relation and comprising a vertical flange and a horizontal flange, a base member disposed above the horizontal flanges of the rail and having downwardly opening sockets, supporting means attached to said horizontal flange and cushioning means between the base member and said supporting means, said supporting means projecting into said sockets to limit movement of the base member toward the vertical flanges of said rails.

6. In combination, a frame, angle rails secured thereto and each comprising a vertical flange and a horizontal flange, a base member disposed above the horizontal flanges of the rails, cushion supporting means between the base member and the horizontal flanges of the rails, and means on said base member cooperating with said supporting means for limiting movement of the base member toward the vertical flanges of the rails.

7. In combination, a frame, angle rails

secured thereto and each comprising a vertical flange and a horizontal flange, a base member disposed above the horizontal flanges of the rails, cushion supporting means between the base member and the horizontal flanges of the rails, and means cooperating with said supporting means for limiting movement of the base member toward the vertical flanges of the rails, the base member being free from said supporting means.

8. In combination, a frame, angle rails secured thereto, each of the rails comprising a vertical flange and a horizontal flange, a base member disposed above the horizontal flanges of the rails and having downwardly opening sockets, the end walls of the base member being disposed in spaced relation to the vertical flanges of the rails, cushion members secured upon the upper faces of the horizontal flanges of the rails, and extending into the lower ends of the sockets, said members limiting movement of the base member toward the vertical flanges of the rails, cushion members disposed within the upper portions of the sockets, and cushion springs confined between said cushion members and spaced away from the surrounding walls of the sockets.

In witness whereof, we hereunto subscribe
30 our names this 25 day of February, 1930.

WILLIAM E. BIHL.
AXEL RAMCLAW.
